COMBINED SASH GUIDE AND WEATHER STRIPPING FOR REMOVABLE WINDOWS

Davis F. Holmes and Minnie Roberta Stork,
Atlanta, Ga.

Application January 22, 1952, Serial No. 267,534

3 Claims. (Cl. 20—52.2)

1

This invention relates to a window construction and more particularly to combined sash guiding channels and weather stripping and it consists in the constructions, arrangements and combinations herein described and claimed.

It is the cardinal object of the invention to provide sash guiding channels wherein the inherent resilience of the channels provide a weather-tight fit with the window frame and sash members and in which a self-equalizing action is provided upon the sash without the need for sash weights, springs or adjusting means, the sash being effectively held against sticking, binding or rattling and will maintain the sash at a desired position against slippage due to vibrations.

More specifically, it is an object of the invention to provide a pair of opposed guide channels for reception of sash, one of the channels being fixed against lateral movement, while the other guide channel is provided with a sash engaging member having a seat for snug reception of a rabbit of the sash, the seat having a lateral resilience exerting a pressure for maintaining the sash seated in the fixed channel, yet yieldable laterally in the opposite direction, permitting ready removal of the sash, as may be required.

It is a still further object of the invention to provide sash guiding channels which are of extremely simple construction and which may be readily installed in new or old building structures by average workmen and with a minimum of labor.

Additional objects, advantages and features of invention will be apparent from the following description, considered in conjunction with the accompanying drawing, wherein

Figure 1 is a horizontal cross section through a double hung window frame embodying the use of the sash guide channels.

Figure 2 is a fragmentary perspective view of the movable guide channel.

Figure 3 is a top plan view thereof.

Figure 4 is a reduced end view of the movable channel illustrating a modified form of means for slidably mounting the free end of the channel.

Figure 5 is a similar view of the fixed channel, and

Figure 6 is a modified form of the movable channel.

In the present instance, we have preferred to illustrate the guide channels in a double hung window construction, in which the sash are vertically slidable.

Attention is first invited to Figure 1 of the drawing, wherein a window frame 10 is shown,

5 having the usual uprights 11 and 12. The upright 11 has a pair of channels 13 formed therein and the upright 12 is provided with a pair of channels 14, the channels 13 and 14 being arranged in opposed relation, as is customary, in order to slidably mount a sash therebetween.

Within respective channels 13 a guide channel 15 is rigidly mounted as will be described, while in the channels 14 a laterally movable guide channel 16 is secured, these guide channels 15 and 16 extending the full vertical lengths of the channels 13 and 14 of the window frame.

10 The guide channels 15 and 16 are formed from a single strip of sheet metal, which in the use of 15 aluminum window sash, will be constructed from spring steel, spring zinc or other suitable metal which will permit free sliding movements of the sash members.

15 As clearly shown in Figures 1 and 5, the channel 15 consists of parallel side walls 17 and 18 of such depth as to be properly accommodated within the channel 13 of a given sized window frame. The wall 17 is bent at right angles and then downwardly to provide a wall 19 which extends parallel to the wall 17 forming a bead 20. The wall 19 is of suitable depth and bent at right angles to form a seat 21 for one vertical edge of a sash as will be explained hereinafter. A second seat 22 downwardly offset with respect to the seat 21 is formed of substantial width. 20 The material of the channel 15 is next bent to form a wall 23 parallel to the wall 18, these walls being connected by a wall 24 forming a bead 25 lying in the same horizontal planes as the bead 20, but of greater width. The walls 17 and 18 25 have their ends inwardly bent to form respective base portions 26 and 27. The base portion 26 terminates approximately beneath the bead 25, while the base portion 27 is of greater length and terminates slightly beyond the medial vertical axis of the channel. The base portion 27 is formed with apertures 28 suitably spaced for reception of mounting screws 29 for securing the guide channels 15 within the channels 13 of the frame. The seat 22 is also formed with an opening 30 aligned with each aperture 28 so as to admit the blade of a screw driver for actuating the screws.

20 The laterally movable channel 16 will now be described, attention being invited particularly to Figures 1 and 2 of the drawing, wherein it will be seen that the guide channel 16 comprises a base foot 31 of a width to occupy the major portion of the channel 14 of the frame and is anchored to the wall of the channel by means of 25 suitably spaced screws 32. The base foot 31 is

integral with a right angular wall 33, which is bent at right angles to define a bead 34. From the bead 34, the material of the channel is bent to form a wall 35 parallel to but spaced from the wall 33. The wall 35 stops short of the base foot 31 and is reversely bent and continues upwardly at an acute angle as at 36 and thence bent in a horizontal plane to form a seat 37. A wall 38 integral with the seat 37 and extended at right angles thereto is bent to form a bead 39 being horizontally disposed in the same plane as the bead 34. A wall 40 integral with the bead 39 is provided, arranged in spaced parallel relation to the wall 38, and the wall 40 terminates in an inwardly directed flange 41 disposed beneath the head 39.

A suitable number of mounting clips 42 are employed in the installation of the guide channels 16 and in the present instance comprises a strip of aluminum bent into substantially Z-shaped formation providing a base 43 which is apertured for reception of suitable screws 44, an integral vertical wall 45 and a horizontal wall 46. However, in Figure 4, a modified means for slidably retaining the free end of the channel 16 is shown, wherein a screw 42' is passed through an opening formed in the flange 41 admitted through an opening formed in the bead 39. The shank of the screw is smooth for the major portion of its length and obviously a series of such screws suitably spaced will be employed in the mounting of the channel.

As clearly shown in Figure 1, the frame 10 includes respective parting strips 47 and 48 positioned between the pair of guide channels 15 and 16. The guide channels 15 are vertically positioned within the channels 13 of the frame 10 and secured therein by means of screws 29, the narrow beads 20 of the guides being presented toward the outsides of the upper sash 49 and the lower sash 50.

The guide channels 16 are next mounted in respective channels 14 of the frame and in this instance, a suitable number of clips 42 are properly positioned in the channels 14 next adjacent but spaced from the parting strip 48 and the inner wall 51 of the frame, with the flanges 46 presented toward the inside of the frame. The guide channels 16 are now positioned in the channels 14 and this is accomplished by presenting the flange 41 behind the horizontal wall 46 of the clip, which may be readily accomplished by virtue of the resilience of the metal forming the parts. It will be noted that the terminal end or flange 41 is unattached and free to be flexed permitting the wall 33 to move into position within the channel 14 of the frame 10. The guide channels 16 are then secured within the channel 14 by screws 32 and since the screws are located rearwardly of the inclined plate 36, openings 52 are formed in the plate to admit the blade of a screw driver. It will be apparent that the plate 36 and associated parts may be moved laterally inward so as to align the openings 52 with the screw heads, so that the screw driver may be readily manipulated.

The inner face of the upper sash 49 and lower sash 50 are each provided with vertical rabbeted edges 53 and 54 respectively, for accommodation of the beads 25 and 39 of the channels 15 and 16.

In order to install the sash within the guides 15 and 16, the upper sash 49 is the first to be placed, which is accomplished as follows: The sash is arranged with the bead 39 seated in the rabbet 53 and a lateral pressure to the left as seen in Figure 1 will flex the inclined plate 36 and associated

parts inwardly of the channel, providing ample clearance to admit the positioning of the opposite side of the sash within the fixed channel 15 and when properly aligned, release of lateral pressure upon the sash, the latter will be moved into engagement within the channel 15. The lower sash 50 will be similarly installed and obviously when it is desired to remove the sash for cleaning or other purposes, the sash is merely moved laterally against the resilient plate 36 until the fixed channel 15 is cleared, and preferably the inner sash 50 would be the first to be removed.

In Figure 6, a modified form of the movable channel is shown, wherein the inclined plate 36' is formed with an intermediate horizontal portion 55 through which an opening 52' is formed, aligned with the mounting screw 32, and eliminates the flexing of the plate 36 to align the opening with the screw.

From the foregoing it will be seen that we have provided guide channels which have a weather-tight fit between the frame and sash members, the latter having a self-equalizing action by virtue of the spring tension of the movable channel and that no adjusting means are required to maintain a snug fit upon the sash members.

While we have shown and described preferred forms of the invention, this is by way of illustration only, and we consider as our own all such modifications in construction as fairly fall within the scope of the appended claims.

We claim:

1. A removable window sash comprising a frame having opposed vertical channels, a sash guide channel secured in one of said vertical channels, said channel being formed from an elongated strip of metal bent to form a pair of vertical extended beads, a seat between said beads; a sash guide channel in the other of said vertical channels, said sash guide channel being formed from an elongated strip of metal bent to form a pair of vertically extended beads forming a channel complementary to the channel formed by the beads of the first mentioned sash guide channel and having a seat between said beads, said seat consisting of a wall having the major portion thereof inclined at an acute angle in the direction of the vertical channel and having one free end to provide lateral movement of said seat and a sash member interposed between seats of said sash guide channels.

2. A removable window sash comprising a frame having opposed vertical channels, a sash guide channel secured in one of said vertical channels, said channel being formed from an elongated strip of metal bent to form a pair of vertically extended beads, a seat between said beads; a sash guide channel in the other of said vertical channels, said sash guide channel being formed from an elongated strip of metal bent to form a pair of vertically extended beads forming a channel complementary to the channel formed by the beads of the first mentioned sash guide channel and having a seat between said beads, said seat consisting of a wall having the major portion thereof inclined at an acute angle in the direction of the vertical channel and having one free end to provide lateral movement of said seat, a sash member interposed between seats of said sash guide channels for vertical sliding movements therealong, said free end having an inturned flange, and mounting means secured within the vertical channel having means for engaging the inturned flange for limiting outward movement of the free end.

3. A double hung window comprising a frame having upright members, a pair of vertical channels in each of the upright members arranged in opposed aligned relation, a sash guide channel in each of one pair of the vertical channels, said channels being formed from a strip of sheet metal bent to form a pair of vertically extended beads having a seat therebetween and further having wall members for engaging adjacent wall portions of the vertical channels and including right angular extensions for fixedly securing the sash guide channel in the vertical channels, a sash guide channel in each of the other pair of vertical channels, said sash guide channel being formed from a strip of resilient sheet metal bent to form a pair of vertically extended beads, the wall forming one side of one of said beads having an angular formation for seating engagement with an adjacent wall and back wall of the vertical channel for securement thereto, the wall forming one side of the other of said beads being free and having lateral sliding movement upon the adjacent wall of the vertical channel,

5

10

15

20

a seat formed between said beads and consisting of a wall inclined at an acute angle from the free end of the slideable wall, the seats of the sash guide channels being in opposed aligned relation, and sash members interposed between opposed aligned seats for vertical sliding movements therealong, the free end of said slideable wall having an inturned flange and clips mounted within the vertical channel having means for engaging the inturned flange for limiting outward movement of the slideable wall.
